UNITED STATES PATENT OFFICE

165,799

POKER CHIP RACK

Clarence H. Stedman, Decatur, Ill.

Application December 5, 1950, Serial No. 13,269

Term of patent 7 years

(Cl. D34—13)

To all whom it may concern:

Be it known that I, Clarence H. Stedman, a citizen of the United States, residing at Decatur, in the county of Macon, and State of Illinois, have invented a new, original, and ornamental Design for a Poker Chip Rack, of which the following is a specification, reference being had to the accompanying drawings, forming a part hereof.

I claim:

The ornamental design for a poker chip rack, as shown.

CLARENCE H. STEDMAN.
